UNITED STATES PATENT OFFICE.

HERBERT EDWARD CRAMPTON STUBBS, OF SRINAGAR, INDIA.

BACK-REST FOR CYCLE-SADDLES.

SPECIFICATION forming part of Letters Patent No. 735,313, dated August 4, 1903.

Application filed January 15, 1902. Serial No. 89,931. (No model.)

To all whom it may concern:

Be it known that I, HERBERT EDWARD CRAMPTON STUBBS, civil engineer, a British subject, residing at Srinagar, in the State of 5 Kashmir, Empire of India, have invented certain new and useful Improvements in Back-Rests for Cycle-Saddles, of which the following is a specification.

This invention relates to adjustable back-rests for cycle-saddles which can be raised or lowered, set back, or brought forward near the back of the saddle to any desired extent to suit the rider, or which can be turned down in a horizontal position and used as a 10 carrier for parcels, or which can be detached altogether when not required, and which can be attached to almost every description of 15 cycle-saddle now in use.

In the accompanying drawings, Figure 1 20 shows a vertical longitudinal section through the center of part of a cycle-saddle supported on spiral springs, with the back-rest attached thereto. Fig. 2 shows a plan view of the top plate of the back-rest carrier-bracket which 25 connects with the spiral-spring-supported saddle. Fig. 3 is a rear elevation of the back-rest, its supporting-standards, and the brackets.

In the drawings the scale may be taken to be about two-fifths of the full size, and in the 30 drawings, Z indicates the saddle-seat, part of which only is shown. The back-rest comprises the part E, which may be made of any suitable material, such as thin board or sheet metal, but preferably of sheet-aluminium. 35 It is leather-covered and slightly padded and is curved to fit the back of the rider. The back-rest also comprises a pair of standards F, which support the part E, said standards being made of steel rod, the upper end of 40 each of which is forged into a flat bar G for attachment to the back of the part E by screws or rivets or other suitable means.

The lower end of each of the standards F is threaded to receive a nut F' to prevent the 45 removal of the rest. Each standard rests in a bracket, which, as shown, consists of a single piece and having a horizontal portion or plate H, a portion I, bent at right angles to the plate H, and the inwardly-bent portion 50 J', which latter portion is turned upward at l. Holes a, b, and c are provided in the plate H for the purpose of shifting the back-

rest farther away from the back of the saddle. Each plate H is inserted between the top plate of seat Z and the head f of each of the 55 spiral springs g and adjusted by a nut d. K is a clamping-ring which encircles each of the standards, the outer end of which is adapted to receive a thumb-screw N. By first adjusting the back-rest to the desired 60 height and then screwing up tightly the thumb-screws N the clamping-rings will be drawn tightly against the standards F to firmly hold the latter in their vertically-adjusted position. 65

When it is desired to use this back-rest as a carrier, it is simply removed from the bracket by unscrewing the nut F' and the clamp K and N inserted in the back plate of the bracket at J, its nut end resting on the 70 toe l, the clamp K N being applied to it through the hole I in the foot of the bracket.

What I claim, and desire to secure by Letters Patent, is—

1. The combination with a cycle-saddle, of 75 a bracket having a series of apertures, a threaded bolt passing through one of the apertures and into the saddle, said bolt being adapted to be inserted through the different apertures whereby to provide for longitudinal 80 movement of the bracket relatively to the saddle, a nut screwing upon said bolt, a back-rest and means for securing the back-rest to the bracket, all arranged as and for the purpose specified. 85

2. The combination with a cycle-saddle, of 90 a bracket having a series of apertures, a threaded bolt passing through one of said apertures and into the saddle, said bolt being adapted to be inserted through the different apertures whereby to provide for longitudinal 95 movement of the bracket relatively to the saddle, a nut screwing upon said bolt, a back-rest, and means for securing the back-rest adjustably to the bracket, all arranged as and for the purpose specified.

3. The combination with a cycle-saddle, of 100 a bracket having a series of apertures, a threaded bolt passing through one of said apertures and into the saddle, said bolt being adapted to be inserted through the different apertures whereby to provide for longitudinal movement of the bracket relatively to the saddle, a nut screwing upon said bolt, a back-

rest comprising standards which pass loosely through apertures in the bracket, said standards being adapted for vertical adjustment in said apertures, and means for securing the standards in adjusted positions.

4. The combination with a cycle-saddle, of a bracket having a horizontal portion H, the portion I and the portion J', said portions H, and J' being provided with alined apertures 10 and said portion H being also provided with apertures a, b, c, a threaded bolt passing through one of the latter apertures and into the saddle, said bolt being adapted to be inserted through the different apertures a, b, 15 c, whereby to provide for longitudinal movement of the bracket relatively to the saddle,

a nut screwing upon said bolt, a back-rest comprising standards which pass loosely through the alined apertures in the portions H, J', and adapted for vertical adjustment 20 therein, and means for securing the standards in adjusted positions.

In testimony that I claim the foregoing as my invention I have signed my name, in presence of two subscribing witnesses at Srinagar, 25 in Kashmir, India, on the 21st day of November, 1901.

HERBERT EDWARD CRAMPTON STUBBS.
